ALTERNATING-CURRENT DIRECT-CURRENT CLOCK

Frank Conrad, Wilkinsburg, Pa., assignor to
Westinghouse Electric & Manufacturing Company, East Pittsburgh, Pa., a corporation of Pennsylvania

Application July 27, 1932, Serial No. 625,147

13 Claims. (Cl. 58—26)

My invention is directed to improvements in clocks or oscillating mechanisms which can be actuated either on alternating current or on direct current, and it has particular relation to a clock which, in its preferred form of construction, is capable of synchronizing itself with the alternations of the source of current therefor when it is being energized from an alternating-current source.

10 My present invention is a modification of a dry-battery clock which constituted the subject-matter of a copending application, Serial No. 178,061, filed March 17, 1927, Patent No. 1,911,062, granted May 23, 1933, for Electric clocks, an important 15 feature of which was a mechanical movement for converting the oscillating movement of the timing shaft or balance-wheel shaft into uni-directional step-by-step rotary movement, the amount of rotary movement being unaffected by the amplitude of the oscillations of the timing shaft, within 20 wide limits, which is necessary in a clock mechanism.

One of the objects of my present invention is to provide a dual electric supply system for a clock of 25 this same general type, said dual supply system comprising a transformer for reducing the voltage of a commercial alternating-current house-circuit to a very low voltage which is rectified by means of a small contact rectifier or its equivalent, and a 30 small flashlight battery, for standby operation when the power is off, said battery being connected in series with an electromagnetic switch on the transformer for cutting the battery in or out according as the transformer is deenergized or 35 energized, the contact rectifier preventing the battery from discharging into the transformer winding when the battery is in operation. It will be understood, of course, that either source of electric current may be utilized separate from the 40 other.

Another object of my present invention is to provide a different type of hairspring mechanism or mounting whereby the hairspring, as distinguished from the universal practice in clocks and 45 watches, is deliberately designed to have a very poor regulation, so that it will increase its speed of vibration when its amplitude increases and contrarily. The use of a timing shaft having such a hairspring, in connection with an electromagnetic 50 operating mechanism which is energized by half-wave impulses received from an alternating-current source, and a rectifier, results in a clock which is capable of adjusting its speed, within certain limits, to the frequency of the impressed 55 alternations, so as to take advantage of the timed

alternations of most commercial alternating-current systems, whether 60-cycle, 25-cycle, or 50-cycle.

A further object of my invention is to equip the electromagnetic driving-mechanism for the timing shaft with a special type of contact make-and-break mechanism which is particularly advantageous in this mechanism.

With the foregoing and other objects in view, my invention consists of the apparatus, systems 10 and methods hereinafter described and claimed, and illustrated in the accompanying drawing, wherein:

Figure 1 is a front elevational view of a clock mechanism embodying my invention, with the 15 front plate removed, as indicated by the section plane I—I in Fig. 2;

Fig. 2 is a side elevational view on a plane looking in a direction indicated by the arrows II—II 20 in Fig. 1;

Fig. 3 is an enlarged sectional view, on the plane III—III in Fig. 2, through the gear mechanism for converting oscillatory movement into rotary movement;

Fig. 4 is a top plan view of the parts shown in 25 Fig. 3, looking in the direction of the arrows IV—IV in Fig. 2;

Fig. 5 contains a sectional view through the oscillating shaft, showing the contact mechanism and the relative positions of the stator and rotor 30 poles, on the plane V—V in Fig. 2, with a diagrammatic representation of the electromagnet coil and other parts of the electric circuit, and

Figs. 6 and 7 are curve diagrams showing, respectively, the uni-directional voltage half-waves 35 which are supplied by the transformer and rectifier, and the current which is admitted into the electromagnet coil by the contact mechanism on the timing shaft.

My timing mechanism comprises a timing shaft 40 carrying a balance wheel 2 having a plurality of pole members 3 and 4 which cooperate with the stationary pole piece 5 of an electromagnet 6 which is mounted on the front plate 7 of the mechanism, said front plate being preferably 45 magnetizable, and of such large area that it provides a fairly good return path, through the air, for the magnetic flux from the electromagnet pole which is attached to the plate.

The oscillating movement of the timing shaft is 50 transmitted to the clock gear train 8 through a mechanical movement which is particularly shown and described in my above-mentioned copending application. As more particularly shown in the enlarged views of Figs. 3 and 4 of the accompany. 55

ing drawing, this mechanism comprises right-hand and left-hand worm-gear elements 10 and 11 carried by the timing shaft 1 and cooperating with a toothed wheel 12 lying in a plane which includes the timing shaft, with the teeth of the toothed wheel extending up close to the timing shaft so as to be engaged by the worm-gear elements 10 and 11. As set forth in my copending application, each of the worm-gear elements 10 and 11 has a short inclined-plane surface 13 and an annularly extending surface 14 which is normal to the timing shaft. Each inclined-plane surface has a limited circumferential extent of n degrees, and each annular normal surface has a circumferential extent of approximately $(360-2n)^\circ$.

Each of the two inclined-plane surfaces 13 has an axial extent greater than a half tooth-pitch of the toothed wheel 12, so that, when the oscillating timing shaft 1 moves in the direction of the arrow 15 in Fig. 4, through any distance or amplitude greater than n degrees, and up to its maximum possible extent of about $(360-n)^\circ$, from its mid-position 16, the inclined-plane surface 13 of the worm-gear element 10 will push the toothed wheel one-half tooth-pitch to the left. When the oscillating timing shaft returns again to its mid-position 16, the inclined surface element 13 moves in between two of the teeth of the toothed wheel 12, and the toothed wheel 12 remains stationary, without any retrograde movement. When the oscillating shaft reaches its mid-position, in this movement which is now contrary to the arrow 15 in Fig. 4, or about this time, the other inclined-plane surface 13 which is carried by the second worm-gear element 11 engages a tooth of the toothed wheel to push it another half tooth-pitch in the same direction as before, thus converting the oscillatory movement of the timing shaft into a step-by-step rotational movement which is unaffected by the amplitude of the timing shaft within the wide limits of n degrees and about $(360-n)^\circ$ in either direction from the mid-position of the shaft.

In the foregoing description of the mechanical movement for converting oscillatory into rotational movement, it was stated that the toothed wheel 12 had no retrograde movement. It is quite essential, in this type of mechanism, particularly when applied to a clock or other precision instrument, to guard positively against any retrograde movement of the toothed wheel 12, which might result either from the resiliency or backlash of the time gear train 8 or from the backward movement of the hands of the clock in the process of setting the same. To this end, as explained in my copending application, I provide the shaft 17 of the toothed wheel 12 with a worm gear or other non-reversible gear mechanism 18, as shown more particularly in Figs. 1 and 2, utilizing this worm gear 18 to drive the clock gear train 8.

The energy for maintaining the oscillations of the timing shaft is provided by means of the above-described electromagnet 6 which receives very brief current-impulses, at predetermined points in the oscillation, under the control of a contact make-and-break mechanism comprising a small pin 20 carried by the timing shaft close to the timing shaft and a contact-making leaf-spring 21, the far end of which is stationarily supported on an insulating post 22. The contact-making leaf-spring 21 is biased to lie in the plane of the timing shaft and extends towards the shaft at right angles thereto so that its near end 24 is engaged by the pin 20 slightly before the

oscillating timing shaft reaches its mid-position in either direction of travel. Thereafter, as the timing shaft continues to move, the pin 20 carries the contact-making leaf-spring 21 to one side, until the timing shaft has traveled a predetermined distance less than n degrees beyond its mid-position, at which time the pin passes around from under the end of the leaf-spring and permits the latter to snap back into its normal position, breaking the contact.

Reference to Figs. 1 and 5 will show that the contact-making leaf-spring is associated with two shorter leaf-springs 25 and 26, one on either side of it, said shorter leaf-springs being supported in the same stationary support and serving the function of damping the vibrations of the contact-making leaf-spring 21 when the latter snaps back into its normal position after breaking contact with the timing-shaft pin 20. The friction between the surfaces of the contact-making leaf-spring 21 and the two shorter leaf-springs 25 and 26 effectually damps any oscillations.

The contact members 20-21 are connected in series with the electromagnet coil 6, so that the latter is supplied with current which begins to flow just before the timing shaft reaches its mid-position. When the shaft is in its mid-position, the two poles 3 and 4 of the balance wheel are at substantially equal distances from the stationary pole 5 of the electromagnet. The current remains in the electromagnet until the timing shaft has moved well past its mid-position, so that the main effect of the electromagnetic flux is developed when one of the moving poles 3 or 4 is much closer to the stationary pole 5 than the other moving pole is, so that the closer moving pole will be attracted to the stationary pole, affording the necessary impulse to maintain the oscillation. This effect of the electromagnet is increased, also, by the time-lag or slowness with which the flux builds up therein and also the slowness with which the flux dies down therein, this latter function being increased by virtue of a high-resistance shunt 28, of perhaps 500 or 1000 ohms, which is connected across the electromagnet coil 6 for the purpose of reducing sparking at the contact members 20-21. In Figs. 1 and 2 this high-resistance shunt 28 is shown in a common commercial form consisting of a core member around which a very fine high-resistance wire is wound, the same being covered with insulation so that it looks like an ordinary insulated wire.

I preferably provide a dual current supply for the electromagnet 6, although it is to be distinctly understood that I may use either one of the current sources by itself. As shown more particularly in Fig. 5, I provide a very small transformer 30 having a high-voltage winding 31 which is adapted to be energized from an ordinary timed-frequency commercial alternating-current line, such as 110-volt house current of either 60-cycle frequency or 25-cycle frequency. The transformer 30 also has a low-voltage winding 32 which supplies a very low voltage to the electromagnet coil 6, through a copper-oxide rectifier 33 or equivalent rectifying device. This rectifier, as shown, comprises an oxide-coated copper plate 34 having a cuprous oxide coating Cu_2O on one side, the oxide-coated surface being in contact with a dissimilar plate 36 of other material such as lead. Such a rectifier has the property of permitting substantial current-flow only in the direction from the oxide coating into the copper, so

that the current flows in the direction of the arrows in Fig. 5.

The transformer 30 is provided with a small air-gap 31 which is by-passed by means of a magnetizable armature 38 which is mounted on a spring 39 so as to be biased to a position away from the core of the transformer 30. The armature 38 carries, at its end, a spring contact member 40 which engages a stationary contact 41 when the transformer is deenergized. When the transformer is energized, the armature 38 is attracted to the core so as to bridge the air-gap 31, and the contact 40-41 is broken. The contact 40-41 is connected in series with a small flashlight battery or single dry-cell 42 which is likewise connected to supply current to the electromagnet 6 through the timing-shaft contact make-and-break device 20-21, whenever the electromagnetic switch 40-41 is closed. It will be noted that the polarity of the copper-oxide rectifier 33 is such as to prevent the discharge of the dry-battery 42 through the low-voltage winding 32 of the transformer.

In the particular design shown in the drawing, the timing shaft 1 makes 150 complete oscillations per minute, so that the half-period of oscillation of the timing shaft, or time between successive makings of the contact mechanism 20-21, is $\frac{1}{3}$ of a second, which is exactly 12 complete cycles on a 60-cycle system or 5 complete cycles on a 25-cycle system. In some cases, a sufficient synchronizing action may be obtained when said half-period of oscillation is equal to an odd number of half-cycles of said commercial-frequency system, particularly when the duration of each contact is less than a quarter-cycle, so that every alternate contact is made during a half-cycle when the current-flow is substantially blocked by the rectifier.

40 The effect of the rectifier 33 is to cut off alternate half-waves of the impressed alternating voltage, one of said cut-off half-waves being indicated by dotted lines 44 in Fig. 6. The result is a series of uni-directional half-waves of voltage 45 which are supplied by the transformer-rectifier aggregate. Fig. 6 shows these voltage half-waves for a 60-cycle supply system.

Every twelfth wave, on a 60-cycle system, or, in general, at equal time intervals which are an exact multiple of the period of the alternating-current system, the timing-shaft contact make-and-break mechanism 20-21 makes a brief contact, which is held for only a short period which should be materially less than a full cycle of 55 the alternating-current supply system and is preferably of the order of $\frac{1}{2}$ cycle of the alternating-current supply circuit or even less. A contact period of nearly one-half cycle of the 60-cycle supply system is indicated at AB in Fig. 7 60 although I believe that my contact period is really somewhat less than this.

The balance-wheel shaft 1 is caused to oscillate by means of a hairspring or balance-wheel spring 46 which is deliberately designed not to keep too good time. This may be accomplished by providing a wide space between the regulator prongs 47 and 48, as distinguished from the usual construction in which these prongs closely embrace the hairspring. The result is that when the 70 balance-wheel shaft 1 is operating through a wide amplitude, say 200° on either side of its mid-position, the clock is running too fast, and when the balance-wheel shaft 1 is oscillating through a small amplitude, say 60° on either side of its 75 mid-position, the clock is operating too slow,

whereas at some intermediate amplitude, such as 150° on either side of the mid-position, the clock is keeping correct time. In this case, n degrees would be 60° .

The result of the foregoing construction is that, when the clock is operating on the rectified alternating-current supply, if there should be a momentary decrease in the frequency of the supply source, the contact periods AB would fall largely or altogether within the alternating-current half-cycles in which no current is supplied by the rectifier, so that the amplitude of oscillation of the timing shaft would decrease, bringing down with it the frequency of oscillation, until the first part of each contact period AB falls within the latter part of a half-cycle of the current which is supplied by the rectifier, as indicated at 50 in Fig. 7 which shows the current supplied to the electromagnet coil under such circumstances. The amplitude of oscillation, and hence the frequency of oscillation, will continue to decrease until a sufficient amount of the half-cycle of current is included in the contact period AB to maintain the precise amplitude of oscillation necessary to cause the clock to run at the correct time, or in accordance with the frequency of the commercial alternating-current system to which the clock is connected. My clock is thus enabled to operate synchronously with the supply system and to follow variations in the supply frequency, up to departures of a small amount, such for example as a quarter of one per cent or one-half of one per cent, more or less than the nominal frequency of 60-cycles, 25-cycles or whatever the frequency is. If the frequency of the supply circuit should depart from its nominal frequency by so great an amount that the clock cannot follow the departure, the clock will continue to run at its own rate, deriving energy impulses, for maintaining the oscillation of the timing shaft, from the alternating-current source, but not keeping in step with the alternating-current source.

The amount of power required by my clock is extremely small. It is so small that, when the clock is operated during off-power periods from a small flashlight battery, the life of the battery is practically its shelf life. The design is such that when the battery is supplying current to the clock, the average strength of the battery current, during the useful life of the battery, is about sufficient to make the amplitude of oscillation of the timing shaft such that the clock keeps correct time, so that in the off-power periods, when the clock is operating off of the battery, or when the clock is operating solely from the battery, without the use of an alternating-current supply source, the clock will keep, on the average, substantially correct time.

While I have illustrated my invention in a preferred form of embodiment and have mentioned figures and proportions of an actual construction, it will be understood that my invention is not altogether limited to these details and that many modifications and changes may be made by those skilled in the art within the spirit of my invention. I desire, therefore, that the appended claims shall be accorded the widest construction consistent with their language and the prior art.

I claim as my invention:

1. An electric timing mechanism adapted to be synchronously operated on a commercial alternating-current timed-frequency power system, comprising a balance wheel having a plurality of spaced magnetizable pole pieces, a balance-wheel

shaft therefor mounted for oscillatory movement in both directions from a mid-position of the balance wheel, a balance-wheel spring therefor, said balance-wheel spring being of a type which causes the oscillating balance-wheel system to materially increase its rate of oscillation when its amplitude increases, contact make-and-break means operated by said balance-wheel system for periodically making a contact for a brief period of time, relative to the total oscillating period, beginning each period of contact slightly before the balance wheel reaches its aforesaid mid-position in either direction of travel, an electromagnetic means having a stationary pole member which is disposed substantially symmetrically with respect to two of said balance-wheel pole pieces when the balance wheel is in its aforesaid mid-position, but which is approached by the one or the other of said two balance-wheel pole pieces when the balance wheel moves from its aforesaid mid-position, according to the direction of movement, and a pair of conductors and rectifier means serially associated in operative relation thereto for supplying a series of discontinuous half-waves of a predetermined potential to said contact make-and-break means and to said electromagnetic means.

2. An electric timing mechanism adapted to be synchronously operated on a commercial alternating-current time-frequency power system, comprising a balance wheel having a plurality of spaced magnetizable pole pieces, a balance-wheel shaft therefor mounted for oscillatory movement in both directions from a midposition of the balance wheel, a balance-wheel spring therefor, said balance-wheel spring being of a type which causes the oscillating balance-wheel system to materially increase its rate of oscillation when its amplitude increases and conversely, contact make-and-break means operated by said balance-wheel system for periodically making a contact for a brief period of time, relative to the total oscillating period, beginning each period of contact slightly before the balance wheel reaches its aforesaid mid-position in either direction of travel, the duration of said contact being materially less than one cycle of said alternating current, an electromagnetic means having a stationary pole member which is disposed substantially symmetrically with respect to two of said balance-wheel pole pieces when the balance wheel is in its aforesaid mid-position, but which is approached by the one or the other of said two balance-wheel pole pieces when the balance wheel moves from its aforesaid mid-position, according to the direction of movement, a voltage-reducing means, and rectifier means associated with the low-voltage terminals of said voltage-reducing means for supplying a series of discontinuous half-waves of a predetermined potential to said contact make-and-break means and to said electromagnetic means.

3. An electric timing mechanism adapted to be synchronously operated on a commercial alternating-current time-frequency power system, comprising a balance wheel having a plurality of spaced magnetizable pole pieces, a balance-wheel shaft therefor mounted for oscillatory movement in both directions from a mid-position of the balance wheel, a balance-wheel spring therefor, said balance-wheel spring being of a type which causes the oscillating balance-wheel system to materially increase its rate of oscillation when its amplitude increases and conversely, contact make-and-break means operated by said balance-

wheel system for periodically making a contact for a brief period of time, relative to the total oscillating period, beginning each period of contact slightly before the balance wheel reaches its aforesaid mid-position in either direction of travel, an electromagnetic means having a stationary pole member which is disposed substantially symmetrically with respect to two of said balance-wheel pole pieces when the balance wheel is in its aforesaid mid-position, but which is approached by the one or the other of said two balance-wheel pole pieces when the balance wheel moves from its aforesaid mid-position, according to the direction of movement, an alternating-current voltage-reducing means, rectifier means permanently associated with the low-voltage terminals of said voltage-reducing means and with said contact make-and-break means and said electromagnetic means for normally supplying a series of discontinuous half-waves of a predetermined potential to said contact make-and-break means and to said electromagnetic means, a battery, and an electromagnetically operated switch for disconnecting the battery when the voltage-reducing means is energized and for connecting the battery to said contact make-and-break means and to said electromagnetic means when the voltage-reducing means is deenergized, the direction of conduction of said rectifier means being such as to substantially keep the battery current out of the voltage-reducing means when the battery is connected in circuit.

4. An electric timing mechanism adapted to be operated on either alternating current or direct current, comprising a balance wheel of a type having poor regulation, a balance-wheel shaft therefor, a balance-wheel spring therefor, contact make-and-break means operated by said balance-wheel system for periodically making a contact for a brief period of time, relative to the total oscillating period, at a predetermined point in the oscillation of the balance wheel, electromagnetic means associated with said contact make-and-break means for periodically supplying a driving-impulse to said balance wheel, a pair of alternating-current conductors and a battery in said timing mechanism, rectifier means permanently serially associated with said alternating-current conductors and with said contact make-and-break means and said electromagnetic means for normally supplying a series of discontinuous half-waves of a predetermined potential to said contact make-and-break means and to said electromagnetic means, and an electromagnetically operated switch for closing its switch-contacts when said alternating-current conductors are deenergized, said switch-contacts being in series with said battery for supplying direct current to said contact make-and-break means and to said electromagnetic means, the direction of conduction of said rectifier means being such as to substantially keep the battery current out of the alternating-current conductors when the battery is connected in circuit.

5. An electric timing mechanism adapted to be synchronously operated on a commercial alternating-current timed-frequency power system, comprising a balance wheel, a balance-wheel shaft therefor, a balance-wheel spring therefor, said balance-wheel spring being of a type which causes the oscillating balance-wheel system to materially increase its rate of oscillation when its amplitude increases and conversely, the half-period of oscillation of the oscillating shaft being approximately equal to a whole number of cycles

of the commercial frequency for which the timing mechanism is designed, contact make-and-break means operated by said balance-wheel system for periodically making a contact for a brief 5 period of time, relative to the total oscillating period, at a predetermined point in the oscillation of the balance-wheel, electromagnetic means associated with said contact make-and-break means for periodically supplying a driving-10 impulse to said balance wheel, a pair of conductors and rectifier means permanently serially associated in operative relation thereto and permanently serially associated in operative relation to said contact make-and-break means 15 and said electromagnetic means for normally supplying a series of discontinuous half-waves of a predetermined potential to said contact make-and-break means and to said electromagnetic means, a stand-by source of power for 20 operating said timing means when alternating-current power is off or disconnected, and said stand-by source comprising a battery, an electro-magnetically operated switch for closing its switch-contacts when said alternating-current 25 conductors are deenergized, said switch-contacts being in series with said battery for supplying direct current to said contact make-and-break means and to said electromagnetic means, the direction of conduction of said rectifier means 30 being such as to substantially keep the battery current out of the transformer when the battery is connected in circuit.

6. An electric timing mechanism adapted to be operated on either alternating current or direct current, comprising a balance wheel of a type having poor regulation, said balance wheel having a plurality of spaced magnetizable pole pieces, a balance-wheel shaft therefor mounted for oscillatory movement in both directions from a mid-position of the balance wheel, a balance-wheel spring therefor, the half-period of oscillation of the oscillating shaft being approximately equal to a whole number of cycles of the commercial frequency for which the timing mechanism is designed, contact make-and-break means 35 operated by said balance-wheel system for periodically making a contact for a brief period of time, relative to the total oscillating period, beginning each period of contact slightly before the balance wheel reaches its aforesaid mid-position in either direction of travel, an electromagnetic means having a stationary pole member which is disposed substantially symmetrically with respect to two of said balance-wheel pole 40 pieces when the balance-wheel is in its aforesaid mid-position, but which is approached by the one or the other of said two balance-wheel pole pieces when the balance wheel moves from its aforesaid mid-position, according to the direction of movement, a step-down transformer, rectifier means permanently associated with the low-voltage side of said transformer and with said contact make-and-break means and said electromagnetic means for 45 normally supplying a series of discontinuous half-waves of a predetermined potential to said contact make-and-break means and to said electromagnetic means, a battery, and an electro-magnetically operated switch for disconnecting the 50 battery when the transformer is energized and for connecting the battery to said contact make-and-break means and to said electromagnetic means when the transformer is deenergized, the direction of conduction of said rectifier means 55 being such as to substantially keep the battery 55

current out of the transformer when the battery is connected in circuit.

7. A time mechanism comprising an oscillating timing shaft, electromagnetic driving-mechanism for causing said timing shaft to oscillate periodically through more than n° and less than $(360-n)^\circ$ in each direction from its mid-position, where n is less than 180, and a contact make-and-break device for controlling said electromagnetic driving-mechanism, said contact 10 make-and-break device comprising a small pin carried by the timing shaft close to the timing shaft and a contact-making leaf-spring supported stationarily at its far end and extending toward the timing shaft so that the near end of 15 the spring is engaged by said pin slightly before the timing shaft reaches its aforesaid mid-position and breaks its contact before the timing shaft has traveled n° beyond its aforesaid mid-position, in either direction of travel, said contact-making spring being biased to return to a central position with respect to the timing shaft, and a shorter leaf-spring on each side of, and in substantially continuous frictional contact with, 20 said contact-making leaf-spring for damping 25 the vibrations of the latter.

8. A time mechanism comprising an oscillating timing shaft, electromagnetic driving-mechanism for causing said timing shaft to oscillate periodically through more than n° and less than $(360-n)^\circ$ in each direction from its mid-position, where n is less than 180, means for causing the oscillation-rate of said timing shaft to materially increase with an increase in amplitude within said limits of n° and $(360-n)^\circ$ from said 35 mid-position, a contact make-and-break device for controlling said electromagnetic driving-mechanism, a pair of alternating-current conductors and a battery in said timing mechanism, rectifier means permanently serially associated 40 with said alternating-current conductors and with said contact make-and-break device and said electromagnetic driving-mechanism for normally supplying a series of discontinuous half-waves of a predetermined potential to said contact make-and-break device and to said electromagnetic driving-mechanism, and an electro-magnetically operated switch for closing its switch-contacts when said alternating-current 45 conductors are deenergized, said switch-contacts being in series with said battery for supplying direct current to said contact make-and-break means and to said electromagnetic driving-mechanism, the direction of conduction of said rectifier means being such as to substantially 50 keep the battery current out of the alternating-current conductors when the battery is connected 55 in circuit.

9. A time mechanism comprising an oscillating timing shaft, electromagnetic driving-mechanism for causing said timing shaft to oscillate periodically through more than n° and less than $(360-n)^\circ$ in each direction from its mid-position, where n is less than 180, means for causing the oscillation-rate of said timing shaft to 60 materially increase with an increase in amplitude within said limits of n° and $(360-n)^\circ$ from said mid-position, a contact make-and-break device for controlling said electromagnetic driving-mechanism, an alternating-current voltage-reducing means, rectifier means permanently associated with the low-voltage terminals of said voltage-reducing means and with said contact make-and-break device and electromagnetic driving-mechanism for normally supplying a se- 65 70 75

ries of discontinuous half-waves of a predetermined potential to said contact make-and-break device and to said electromagnetic driving-mechanism, a battery, and an electromagnetically operated switch for disconnecting the battery when the voltage-reducing means is energized and for connecting the battery to said contact make-and-break means and to said electromagnetic driving-mechanism when the voltage-reducing means is deenergized, the average amplitude of oscillation produced by said voltage-reducing means and rectifier means being about the same as that produced by said battery.

10. A time mechanism comprising an oscillating timing shaft of a type having poor regulation, electromagnetic driving-mechanism for causing said timing shaft to oscillate periodically through more than n° and less than $(360-n)^\circ$ in each direction from its mid-position, where n is less than 180, a contact make-and-break device for controlling said electromagnetic driving-mechanism, an alternating-current voltage-reducing means, rectifier means permanently associated with the low-voltage terminals of said voltage-reducing means and with said contact make-and-break device and said electromagnetic driving-mechanism for normally supplying a series of discontinuous half-waves of a predetermined potential to said contact make-and-break device and to said electromagnetic driving-mechanism, a battery, and an electromagnetically operated switch for disconnecting the battery when the voltage-reducing means is energized and, for connecting the battery to said contact make-and-break means and to said electromagnetic driving-mechanism when the voltage-reducing means is deenergized.

15. A time mechanism comprising an oscillating timing shaft, electromagnetic driving-mechanism for causing said timing shaft to oscillate periodically through more than n° and less than $(360-n)^\circ$ in each direction from its mid-position, where n is less than 180, means for causing the oscillation-rate of said timing shaft to materially increase with an increase in amplitude within said limits of n° and $(360-n)^\circ$ from said mid-position, a contact make-and-break device for controlling said electromagnetic driving-mechanism, and a pair of alternating-current supply-conductors and rectifier means associated in operative relation thereto for supplying a series of discontinuous half-waves of a predetermined potential to said contact make-and-break means and to said electromagnetic driving-mechanism, said contact make-and-break device comprising a small pin carried by the timing shaft close to the timing shaft and a contact-making leaf-spring supported stationarily at its far end and extending toward the timing shaft so that the near end of the spring is engaged by said pin slightly before the timing shaft reaches its aforesaid mid-position and breaks its contact before the timing shaft has traveled n° beyond its aforesaid mid-position in either di-

rection of travel, said contact-making spring being biased to return to a central position with respect to the timing shaft, and a shorter leaf-spring on each side of, and in substantially continuous frictional contact with, said contact-making leaf-spring for damping the vibrations of the latter.

12. An electric timing mechanism adapted to be synchronously operated on a commercial alternating-current timed-frequency power system comprising an oscillating timing shaft, electromagnetic driving-mechanism for causing said timing shaft to oscillate periodically through more than n° and less than $(360-n)^\circ$ in each direction from its mid-position, where n is less than 180, means for causing the oscillation-rate of said timing shaft to materially increase with an increase in amplitude within said limits of n° and $(360-n)^\circ$ from said mid-position, a contact make-and-break device operated by said timing shaft for periodically making a contact slightly before the timing shaft reaches its mid-position and breaking said contact before the timing shaft has traveled n° beyond its mid-position, in either direction of travel, said contact make-and-break device being connected to control said electromagnetic driving-mechanism, the angular velocity of said oscillating timing shaft near its mid-position and the angle of duration of one of said contacts being such that the time of duration of one of said contacts is materially less than one cycle of the commercial frequency for which said timing mechanism is designed, and a pair of alternating-current supply conductors and rectifier means serially associated in operative relation thereto for supplying a series of discontinuous half-waves of a predetermined potential to said contact make-and-break means and to said electromagnetic driving-mechanism.

13. A time mechanism comprising an oscillating timing shaft of a type having poor regulation, electromagnetic driving-mechanism for causing said timing shaft to oscillate periodically, a contact make-and-break device operated by said timing shaft for controlling said electromagnetic driving-mechanism, a pair of alternating-current conductors and a battery in said timing mechanism, rectifier means permanently serially associated with said alternating-current conductors and with said contact make-and-break device and said electromagnetic driving-mechanism for normally supplying a series of discontinuous half-waves of a predetermined potential to said contact make-and-break device and to said electromagnetic driving-mechanism, and an electromagnetically operated switch for closing its switch-contacts when said alternating-current conductors are deenergized, said switch-contacts being in series with said battery for supplying direct current to said contact make-and-break means and to said electromagnetic driving-mechanism.

FRANK CONRAD.
